HEADLIGHT FOR SUCTION CLEANERS

Filed Nov. 14, 1947

UNITED STATES PATENT OFFICE

2,594,524

HEADLIGHT FOR SUCTION CLEANERS

John Edward Vance, Canton, Ohio, assignor to
The Hoover Company, North Canton, Ohio, a
corporation of Ohio

Application November 14, 1947, Serial No. 786,033

6 Claims. (Cl. 15—324)

1

The present invention relates to suction cleaners in general, and more particularly to a new and improved headlight construction for a suction cleaner. More specifically, the invention comprises an improved construction in which the light source is positioned and carried in a new and novel manner.

It is an object of the present invention to provide a new and improved suction cleaner.

It is another object to provide a new and improved suction cleaner casing embodying floor-illuminating means.

A further object is to provide means on the casing for supporting a light to one side of the vertical axis of a horizontal motor type ambulatory suction cleaner with means to direct the light rays emitted from the light onto the surface covering undergoing cleaning immediately forward of the suction cleaner nozzle.

A still further object is the provision of a headlight for a suction cleaner which is so arranged that it makes use of unused space within the normal confines of the cleaner body above the nozzle and adjacent to the motor fan unit in order to simplify the wiring for the light by positioning it adjacent to the electrical circuit of the motor.

Another object of the invention is to provide a floor-illuminating means suitably positioned with respect to the converter construction of the suction cleaner to provide for ready access to the converter in off-the-floor cleaning.

Another object of the invention is to provide simplified wiring and mounting means for the light source.

Another object of the invention is to provide suitable louver construction for directing the light rays emitted from the light to a position immediately forward of the suction cleaner nozzle.

Still another object of the invention is to provide a novel motor case construction in which the light source is mounted thereon eccentric with respect to the vertical axis of the motor.

These and other more specific objects will appear upon reading the following specification and claims and upon considering in connection therewith the attached drawings to which they relate.

According to the present invention, a vacuum cleaner assembly in the form of a horizontally positioned motor fan unit having a nozzle extending angularly relative thereto is provided with a light located in a space to one side of the fan chamber and to the rear of and to one side of the converter opening and so positioned to direct the light rays emitted by the light onto the sur-

2

face immediately forward of the nozzle. In order to direct the rays forwardly of the nozzle, a suitable ornamental closure is provided to confine the light source and to direct its rays forwardly of the nozzle while at the same time enhancing the appearance of the cleaner body.

In the drawings, in which a preferred embodiment of the present invention is disclosed, like reference characters indicate the same or similar parts.

Figure 1 is a front view of the suction cleaner with floor-illuminating means embodied therein in accordance with the present invention;

Figure 2 is a side elevation, partly in section, taken along line 2—2 of Figure 1;

Figure 3 is a plan view, partly in section, taken along line 3—3 of Figure 1 looking in the direction of the arrows; and

Figure 4 is a view in elevation taken along line 4—4 of Figure 2 looking in the direction of the arrows.

With the advent of smaller dwelling units and apartments, it has been in keeping with the trend to develop smaller suction cleaners of the ambulant type which may be readily stored and which may be sold at a lower cost to the consumer. The trend in these lower cost cleaners has been to leave off a useful part of the suction cleaner such as the headlight or the converter attachments or both. In reducing the size of a suction cleaner, there is only a limited space in which to apply a light whereby the electrical connections to the light may be connected into the electrical circuit of the cleaner proper. In the prior art, it has been taught that a light may be mounted in the forward portion of the cleaner nozzle forwardly of the fan housing but this increases the cost and necessitates that the wiring for the light be led around the cleaner nozzle and fan casing to a point where it may be electrically connected into the electrical circuit of the motor.

According to the present invention both a headlight and provisions for converting to off-the-floor cleaning are provided in a low cost cleaner. That is done by placing the converter opening in the front wall of the suction passage immediately in front of the fan eye and in placing the light and its housing to one side of the fan casing proper above the main frame and inwardly of its outer periphery whereby the light may be directly electrically connected into the motor circuit. In order to provide a symmetrical appearance for the cleaner a similar "dummy" housing is positioned on the opposite side of the fan cas-

Referring to the drawings, there will be described a preferred embodiment of a modern low cost suction cleaner of the horizontal axis type to which the invention has been applied. The suction cleaner comprises a suction nozzle 15, and a fan chamber 16 which houses a suction-creating fan 17. The chamber 16 is interiorly connected through a fan eye 18 to the floor-contacting nozzle 15 in order that it may draw cleaning air therethrough to remove the foreign matter in the surface covering and discharge it through an outlet 19 into a suitable dust bag (not shown) as is well understood. A motor casing 20 is rigidly attached to the fan chamber 16 and houses a suitable driving motor for the suction-creating fan 17. A suitable form of agitator mounted within the suction-creating nozzle 15 may be suitably driven by means of a belt actuated from an extension 21 of the motor shaft. Front supporting wheels 22, 22 and rear wheels 23, 23 make possible the easy movement of the cleaner over the surface covering upon the exertion by the operator of a slight force through a handle (not shown) mounted upon a pivoted bail construction 24 operatively connected to the motor housing. Handle detent means 25 permits adjustment of the handle from its non-operating vertical storage position to its operating position.

A suction passage 26 provides for the passage of dirt laden air from the suction cleaner nozzle 15 to the fan eye 18. The belt which drives the agitator also passes through the suction passage 26. Immediately in front of the fan eye 18 is a converter opening closed by a suitable closure 27 which seals the suction passage from the atmosphere. When the closure 27 is removed a converter attachment may be inserted through the opening so as to communicate with the fan eye 18 in a manner well known in the art. The cleaner is also provided with a furniture guard 29 in any manner well known in the art.

In a low cost type suction cleaner of reduced size particularly with respect to the width of the cleaner, it is also essential in the design of such a suction cleaner that the over-all height of the machine be as low as possible. This requirement is essential when it is considered that the lower the machine is to the floor the greater will be its field of usefulness as it can be used under a greater number of heavy objects such as furniture which are normally positioned upon and overlying the surface covering to be cleaned. In addition, it is further essential that the nozzle 15 be as free of obstructions as possible. For example, the suction passage and fan chamber should be positioned rearwardly of the front edge of the nozzle to permit the nozzle to be readily moved about and underneath the furniture during the cleaning operation. In order to preserve the low height of the cleaner without increasing its width the main casting is provided with symmetrically positioned pockets 30 spaced laterally of the fan chamber 16 to the rear of the suction passageway 26 above the nozzle 15 as is illustrated in Figures 1 to 3, inclusive. As shown in Figures 1 and 3, the pockets 30 are positioned equal distances from the converter opening cover plate 27 on opposite sides thereof. Each of the chambers 30 is provided with an ornamental louvered closure plate 31 which may be formed from sheet metal or plastic and which is readily snapped into position with an extension 32 fitting the opening 33 to each chamber 30. The left hand chamber as viewed

in Figures 1 and 3 is a "dummy" chamber covered with a louvered closure plate 31 to hide the exhaust outlet so as to preserve the symmetrical appearance of the cleaner.

The walls of the right hand pocket 30 are so shaped and curved that they form reflectors adapted to throw light beams forward of the nozzle 15 and across the entire width thereof as indicated by the dashed line 34 in Figures 2 and 3. The closure plate 31 is provided with suitable louvered openings 35 so that light beams are projected forwardly and downwardly from a bulb 36. The bulb 36 which may be a standard bayonet joint type is mounted in a bayonet joint socket 37 formed integrally with an extension of the plastic motor casing 20. A passage 39 extends laterally from the casing 20 and serves to connect the socket 37 to the interior of the motor housing 20.

The passage 39 forms a chamber for receiving spring contacts 40 and 41 the inner ends of which are secured to the wall 38 of the casing 20 by means of screws 44 threaded into insulating lugs 42. At their inner ends the spring contacts are electrically connected into the motor circuit by lead wires 43 also secured by the screws 44. The outer ends of the spring contacts make resilient contact with the contacts of the bulb 36 and serve to hold the bulb in the socket 37 in a manner well known in the art. The front wall 38 of the motor housing 20 is suitably ribbed at 45 to form the rear walls of the chamber 30 and of the fan chamber 16. An ornamental plug 46 serves to form a closure for an opening 47 formed during the molding operation.

The closure 31 may be removed by pulling outwardly so as to disengage the portion 32 from the edges of the opening 33 and the catch 48 from the opening 49 in the top of the nozzle 15 whereby access may be had to the pocket 30 in order to install or replace the bulb 36 in the usual manner.

The bulb 36 is located at substantially the horizontal axis of the motor. The interior of the chamber 30 is coated with enamel or other reflective coating to serve as a reflector for directing the light rays emitted forwardly and downwardly across and in front of the suction nozzle at an angle onto the surface immediately forward of the nozzle 15, as illustrated schematically by the dashed lines 34 in Figures 2 and 3.

While I have shown but a single embodiment of my invention it is to be understood that this embodiment is to be taken as illustrative only and not in a limiting sense. I do not wish to be limited to the particular structure shown and described but to include all equivalent variations thereof except as limited by the scope of the claims.

What is claimed is:

1. In a suction cleaner, an integral body forming a nozzle and a fan chamber, a suction passage in said body forward of the fan chamber and operatively connected to the eye of said fan, said passage being formed with a converter opening in front of the eye of said fan, said nozzle being the element of maximum width of said cleaner and said fan chamber being the element of maximum height, a reflecting chamber formed integrally with said body and laterally of said fan chamber and another chamber symmetrically formed with respect to said reflecting chamber on the opposite side of said fan chamber, ornamental louvered cover plates for each

of said chambers, and a common removable closure plate forming the rear walls of said fan and reflecting chambers.

2. In a suction cleaner, an integral body forming a nozzle and a fan chamber, said nozzle being the element of maximum width of said cleaner and said fan chamber being the element of maximum height, a reflecting chamber formed integrally with said body and spaced laterally of said fan chamber, said fan and reflecting chambers being formed with an opening in the rear thereof, a motor housing fixed to the rear of said chambers, the front wall of said motor housing forming the rear wall of said fan and reflecting chambers upon assembly therewith.

3. In a suction cleaner, an integral body forming a nozzle and a fan chamber, a reflecting chamber formed integrally with said fan chamber and nozzle, a motor housing fixed to said cleaner body and forming the rear wall of said chambers, said motor housing having a light socket thereon positioned to receive a light within said reflecting chamber, a passage formed in the front wall of said motor housing and connecting said socket with the interior of said housing, and spring-biased contacts mounted within said passage and operatively connected to said light whereby said light is spring-biased into said socket, said spring-biased contacts being electrically connected into the circuit of said cleaner.

4. In a suction cleaner, a horizontal axis fan chamber having a forwardly directed suction opening, said nozzle being interiorly connected to said suction opening, a reflecting chamber forming a pocket having a front opening adjacent to said nozzle and fan chamber and laterally positioned with respect to said fan chamber, light creating means in said reflecting chamber, said chamber being shaped as a reflector to direct light outwardly of said pocket in front of said nozzle upon the surface undergoing cleaning immediately forward of said nozzle, a light directing louvered cover forming a closure for said reflecting chamber, conducting means connecting said light creating means to a source of electricity and a common closure plate forming the rear walls of said fan and reflecting chambers, said closure plate forming a support

for said light creating means and a conduit for said conducting means.

5. A suction cleaner comprising, a housing, said housing including a nozzle, means for mounting said housing for ambulatory movement over a surface with said nozzle positioned above said surface, a horizontal axis motor fan unit positioned above and to the rear of said nozzle, said motor fan unit having a forwardly directed suction eye, a suction passage connecting said nozzle to said eye, the forward wall of said passage being formed with a converter opening immediately in front of said suction eye, said nozzle extending laterally of the width of said motor fan unit, said housing having pockets on either side of said converter opening above said nozzle laterally of said motor fan unit to the rear of said suction eye and within the lateral width of said nozzle, a light in one of said pockets and a partition dividing said motor-fan unit into a fan chamber and a motor chamber and forming the rear wall of said one pocket.

6. A suction cleaner according to claim 5 in which said partition forms a support for said light and a conduit formed in said partition for housing electric conductors electrically connecting said light to the motor circuit.
